UNITED STATES PATENT OFFICE.

DAVID F. ESHLEMAN, OF WAYNESBORO, PENNSYLVANIA.

HAY-ELEVATOR.

1,250,824.

Specification of Letters Patent. Patented Dec. 18, 1917.

Application filed April 27, 1917. Serial No. 164,934.

To all whom it may concern:

Be it known that I, DAVID F. ESHLEMAN, a citizen of the United States, residing at Waynesboro, in the county of Franklin and State of Pennsylvania, have invented certain new and useful Improvements in Hay-Elevators, of which the following is a specification.

This invention relates to grain or hay elevators and has for its object the provision of an elevator by which hay or grain may be conveyed from a wagon or other supply into a warehouse or onto a stack and delivered at such point as may be desired to accomplish an even distribution of the material.

The invention is illustrated in the accompanying drawings, in which:

Figure 1 is a front elevation of an apparatus embodying my present improvements;

Fig. 2 is a side elevation of the same;

Fig. 3 is a horizontal section taken just above the upper support;

Fig. 4 is a horizontal section taken just above the lower support;

Fig. 5 is a perspective view showing a different form of the elevator;

Fig. 6 is a detail perspective view.

It is to be understood that my improved apparatus may be mounted upon any fixed support so as to deliver the hay at a desired point, but I have illustrated it as mounted upon the side of a barn, a portion of which is indicated at 1. Upon a beam or other member, immediately below an opening in the upper portion of the barn, I secure a bracket 2 having a pivot pin or stud 3 on its upper side and upon the said stud or pin I engage a frame 4 which has an arcuate inner edge, as shown at 5 in Fig. 3, and rests upon the bracket 2 in such manner that it may oscillate about the pin or stud 3. The outer ends of this frame 4 are secured to the side bars 5' of the elevator frame, the said side bars being braced at suitable intervals by cross bars 6. The lower ends of the side bars have mounted therein a shaft 7 and upon the said shaft, at the outer sides of the bars, are sprocket wheels 8 over which sprocket chains 9 are trained. The said shaft 7 has its ends journaled in the outer extremities of a yoke or horizontally disposed base frame 10, and a sprocket 11 is secured upon one extremity of the shaft, said sprocket being connected by a chain 12 with a sprocket 13 on the outer end of a shaft 14

which is journaled in one side of the frame or yoke 10 and has its inner end supported by a bracket 15 secured upon the inner side of the frame at about the center of the same. Within the said bracket 15 a beveled gear 16 is secured upon the end of the shaft 14 and this beveled gear meshes with a similar gear 17 on the outer end of a short shaft 18 which is connected by a universal joint 19 with the axle or shaft 20 of a driving pulley 21. The said pulley 21 is housed by a bracket or strap 22 in which the shaft or axle 20 is journaled and a band 23 is trained around the said pulley so as to impart motion thereto from any convenient motor. The bracket 22 supports the axle or shaft 20 so that the pulley 21 will be held in proper operative position and will, consequently, impart motion to the movable parts so that the apparatus will operate evenly and steadily while the universal joint 19 permits the base frame 10 to swing freely from side to side, as may be desired, so that the elevator may be caused to deliver the material at any desired point. Braces 24 extend between the sides of the base frame or yoke 10 and the side bars 5' so that the said parts will be maintained in a fixed relation and collapse of the frame will be prevented.

The side bars 5' are secured to the outer ends of the sides of the upper frame 4 and project upwardly beyond the same, a shaft 25 being mounted in the said upper extremities of the side bars and being equipped at their ends with idler sprockets 26, as shown. A supplemental frame consisting of side bars 27 and suitable cross bars bracing the same is pivotally mounted upon the shaft 25 and extends laterally therefrom so as to project into the warehouse, and a shaft 28 is journaled in the ends of the said side bars 27 and carries idler sprockets 29. Braces 30 are secured to the sides of the frame 4 and extend upwardly and outwardly therefrom to the shaft 25 so as to properly support the said shaft and idler sprockets 31 are adjustably mounted upon the said braces 30, as shown clearly in Fig. 2. The chains 9 run over the sprocket 7 at the lower end of the side bars 5' and over the idler sprockets 29 at the ends of the side bars 27, the intermediate portions of the chains passing over the sprockets 26 and 31 and the necessary tension being placed upon the chains by adjusting the idlers 31, as will be readily un-

derstood. Braces 32 extend from the frame 4 downwardly to the side bars 5' and bracing supports 33 are pivoted at their upper ends to the side bars 27 and at their lower ends 5 are adjustable upon the frame 4 so that the said side bars 27 may be raised or lowered as may be needed to accommodate the increasing height of the stored material.

The several braces are, of course, so 10 shaped, as shown for instance at 34 in Fig. 3, as to pass around the runs of the elevator chains 9 and be secured to the side bars 5' or 27 and thereby attain the desired rigidity of the structure without interfering in any 15 way with the free movement of the chains.

Near the lower ends of the side bars 5', I 20 secure a platform 35 to receive the material to be loaded into the barn. This platform consists of an open frame secured to and projected outwardly from the side bars and 25 extending around the elevator chains 9. The frame constituting the platform is curved upwardly toward its outer end so that it will in effect constitute a basket or receptacle 30 which will prevent the hay or other material from rolling or dropping from the platform and will hold it in position to be engaged by the forks or shelves upon the chains. Braces 36 are secured to the sides of the platform and the side bars 5' so as to further strengthen the structure.

As shown in Figs. 1 and 4, the platform may be provided with fingers or bars 37 extending inwardly from its outer edge so as 35 to support the material until it is engaged by the forks or shelves of the carrier and at the same time provide space through which said forks or shelves may move. At intervals along the conveyer chains, I secure 40 forks or shelves 38, the said chains being connected at intervals by cross rods or pins 39, as will be readily understood. The forks or shelves consist of tines or fingers 40 having their inner portions coiled or wrapped 45 loosely around one cross rod 39 and thence extended downwardly, as shown at 41, to bear against the outer side of the next succeeding cross rod 39, thereby preventing the downward movement of the fork under the 50 load imposed thereon. A central tine 42 is provided and has its inner end wrapped loosely around the cross bar 39 but is not extended downwardly therefrom and a bar 43 serves to connect the several tines so that 55 they will form a rigid structure and will effectually support the rod, as will be readily understood. To prevent endwise movement of the shelf or fork, stop collars 44 are secured upon the rod 39 which carries the shelf 60 at opposite sides of the central tine, as shown in Fig. 6.

The operation of the apparatus will be 65 readily understood. The hay is placed upon the platform 35 and motion imparted to the pulley 21 so that the described train of

gearing is set in motion and the conveyer chains actuated. The forks or shelves are thereby carried upwardly through the platform and will engage against the under side of the load or bundle placed thereon and consequently carry the load from the platform up to and over the upper end of the apparatus where it will be discharged onto the stored material. As the quantity of the stored material increases and the surface 70 of the same rises within the warehouse, the frame may be easily swung to one or the other side so that the point of delivery will be shifted laterally within the barn or warehouse and the material stored evenly 75 throughout the storage space. It will be readily noted that my apparatus is exceedingly simple in the construction and arrangement of its parts and may be very easily mounted upon any building without 80 requiring any alterations therein.

In Fig. 5 I have illustrated a modified arrangement of the apparatus in which instead of employing two chains having forks or shelves disposed between them, I employ 90 a single chain which is secured to the several forks at the centers thereof. The driving pulley 50 in this form of the apparatus is mounted within a bracket 51 and is connected by a universal joint 52 with the gearing 53 mounted within a base frame 54. The gearing 53 is connected by chain and sprocket with the shaft 55 mounted in the outer ends of the frame 54 and provided with a sprocket 56 at its center over which 100 the conveyer chain 57 runs. Brackets 58 are secured to the opposite sides of the standard or supporting bar 59 at the lower end of the same and form bearings for the shaft 55 at the opposite sides of the sprocket 105 56. To the upper end of the standard or supporting bar 59, I secure brackets or braces 60 in which a shaft 61 is journaled, coacting blocks or bearings 62 being pivotally mounted upon said shaft and a sprocket 110 63 being carried by the said shaft between the said blocks or bearings. An upper supporting bar 64 is secured between the bearings 62 and extends upwardly therefrom and is provided on its outer extremity with 115 a fork 65 in which an idler sprocket 66 is mounted, the conveyer chain 57 passing over the said idlers 63 and 66 and also over an idler 67 which is carried by a frame 68 secured to and extending rearwardly from 120 the supporting bar 59 and of such dimensions that the forks 69 carried by the chain may readily pass therethrough. Braces 70 extend from the supporting bar 59 to the frame 68 and other adjustable braces 71 extend from the said frame 68 to the upper supporting bar 64. An upper supporting frame 72 is secured to the standard or bar 59 and is pivotally mounted upon a bracket 73 which is secured to the side of the build- 125 130

ing, as will be readily understood, while braces 74 extend from the said supporting frame 72 to the bar 59, as shown. A platform or open supporting frame 75 is provided near the lower end of the standard 59 and braces 76 extend between the said platform and the said bar, as shown. The forks or shelves in this form of the apparatus are provided with end tines only and these tines project from the ends of the bars or arms 77 which are carried by links of the chain 57, as clearly shown in Fig. 5. If desired, guard rails may be extended between the sprockets 63 and 66 to prevent the bundles from twisting and to insure their dumping as the chain passes over the sprocket 66.

Having thus described the invention, what is claimed as new is:

- 20 1. In an apparatus for the purpose set forth, the combination of a conveyer frame, a base frame, a shaft mounted in the outer end of the base frame and the lower end of the conveyer frame, a bracket secured with 25 in the base frame at the inner end thereof, a bracket disposed at the rear of the base frame, gearing supported by the base frame and the bracket therein to operate the con-

veyer on the conveyer frame, shafts journaled in the base frame and the bracket at 30 the rear of the same and having a universal connection between the frame and the bracket, the forward one of said shafts being connected with said train of gearing, a driving pulley on the rear one of said 35 shafts, and means for actuating said pulley.

2. The combination of a fixed support, a vertical pivot thereon, a conveyer frame disposed in spaced relation to the support, a pivot frame secured rigidly to and extending rearwardly from an upper portion of the conveyer frame to engage the pivot and support the conveyer frame for oscillation in a horizontal plane, a base frame secured to and projecting rearwardly from the lower 45 end of the conveyer frame, a conveyer mounted on the conveyer frame, and gearing supported by the base frame and the fixed support to impart motion to the conveyer, said gearing including a universal joint between the base frame and the fixed support 50 whereby the base frame may follow the horizontal oscillation of the pivot frame.

In testimony whereof I affix my signature.

DAVID F. ESHLEMAN. [L. S.]
